UNITED STATES PATENT OFFICE.

JOHN E. FEFEL, OF BRIDGEPORT, CONNECTICUT, ASSIGNOR OF ONE-HALF TO FRANK J. HOEY, OF NEW YORK, N. Y.

FABRIC-WEAVING MACHINE.

Application filed May 21, 1926. Serial No. 110,619.

My invention relates to improvements in fabric weaving machines and has for its object to provide a machine of this type, preferably adapted for weaving a narrow ribbed bon-like fabric—as tape, braid, and the like. A specific object of the invention is to provide a fabric-weaving machine adapted for weaving fabric like that disclosed and claimed in my co-pending application, Serial No. 97,230, filed March 25, 1926, and in which a reinforced selvage is provided at each longitudinal edge.

It is the purpose of my present invention to provide a novel means for handling the weft or filling threads in a fabric without the use of a bobbin, shuttle, or the like, and to employ in their stead needles and loopers of novel construction and arrangement which are associated to cooperate in a way to successively lay the weft threads in the warp, and to loop the same in a manner to form a selvage of the same structure and strength at each edge of the fabric.

I have further shown means and mechanism for operating these weft-handling needles and loopers, but which obviously may be varied somewhat in their arrangement or detail of construction and are, therefore, subject to such changes as may be necessary, and permissible within the scope and breadth of the claims to follow.

By the use of needles and loopers as applied and operated in my invention, I am able to take the filling threads direct from the source—as, for instance, a spool—thereby eliminating the labor involved in winding this vast amount of material upon bobbins, as is customary with the old style of weaving machines, thereby saving a great amount of floor space as is now required for this preliminary work.

With the above and other objects in view, an embodiment of the invention is shown in the accompanying three sheets of drawings, and this embodiment will be hereinafter more fully described with reference thereto, and the invention will be finally pointed out in the claims.

In the drawings forming a part of this specification:

Fig. 1 shows a front elevation of a fabric-weaving machine, according to the present embodiment of the invention.

Fig. 2 is an edge view as seen from the right of Fig. 1.

Fig. 3 is an enlarged sectional view through the rack and pinion mechanism, taken on line 3 of Fig. 2.

Fig. 4 shows a plan view of a sample of fabric woven by my improved machine.

Figs. 5, 6, 7, and 8 are front and plan diagrammatic views respectively, showing steps in the fabric weaving operations of the needles and cooperating loopers carried in the frame members of the weaving machine;

Figs. 9 and 10 are plan views showing further steps.

Similar reference characters indicate corresponding parts throughout the several figures of the drawings.

Referring, in detail, to the characters of reference marked upon the drawings, the machine includes uprights 12 and 13 which may be mounted upon a base 14 and tied together at their upper portions by means of a horizontally-disposed front plate member 15 which serves to support and carry different parts of the machine, as will later be more fully explained.

The main drive shaft 16 is mounted in bearings 17—17 of the uprights and a third bearing 18 which, like the uprights, is also supported upon the before mentioned base 14. This shaft is provided with driving means, as, for instance, a pulley 19, and also has mounted upon it, intermediate of the bearings 17 and 18, cams 20 and 21, again to be referred to. An eccentric 22 is mounted upon this shaft intermediate of the bearings 17—17 as are also cams 23 and 24, which will later be more fully described. On the end of the shaft is mounted a bevel pinion 25 that meshes with and drives a similar bevel pinion 26 secured on an upwardly-extending diagonally-disposed shaft 27 that is journaled in bearings 28—28 secured to the upright 12. A third pinion 29 is mounted upon the upper end of the shaft 27 and meshes with and drives a fourth pinion 30 secured to a transverse shaft 31 journaled in the upper portion of the uprights 12 and 13.

A third transverse shaft 32 also has its end portions journaled in bearings of the uprights 12 and 13 and serves to carry a drum 33 upon which the fabric is wound after being woven. A ratchet 34 is secured to the drum and is operated by a pawl 35 carried upon a rocker-arm 36 journaled upon the shaft 32. One end of a reciproca-

ble connecting rod 37 is pivotally connected to the outer end of this rocker-arm, the other end being attached to a band 38 which encircles and is carried by the eccentric 22 mentioned above.

By this means it will be seen that the drum may be slowly rotated, step by step, through the rotation of the shaft 16, its eccentric 22 and the pawl and ratchet mechanism connected with the drum. In practice these operations are suitably timed so that the fabric is wound upon the drum as it is woven by the action of the weaving mechanism.

15 The mechanism for handling and laying the warp threads may be similar to that employed in ordinary weaving machines, and, therefore, I have not attempted to show it complete in all respects, but have shown (see 20 Fig. 2) a harness 39 whereby the alternate warp threads are raised and lowered and thus woven around the weft or filling threads in the usual manner. These warp threads (which I will indicate as *a—a*) may be taken 25 from a roll 40 mounted upon a standard 41, said roll adapted to be rotated as the warp threads are drawn therefrom, against the resistance of a weight 42 attached to a strap 43 which encircles a reduced part of the roll. 30 44 represents a reed, such as is commonly employed in weaving machines, to pack the weft or filling threads; and which, in this instance, is carried in the upper ends of vertically-disposed rocker-arms 45—45 hinged 35 to a floor bracket 46, and each carrying a roll 47 for engagement with the cams 23 and 24 mounted upon the before mentioned shaft 16. From this construction, it will be seen that the operation of the cams through their 40 engagement with the rolls of the rocker-arms 45 will cause the latter and their reed 44 to be operated forward and backward to and from the woven fabric with each shifting of the harness, and laying of the filling threads 45 in a way to pack said threads against the warp threads in the usual manner.

The particular type of fabric which the machine is adapted to produce is shown in Fig. 4, and comprises the warp threads *a—a* 50 and two weft threads *b* and *c* successively worked into the warp from opposite sides, the laying of each thread being in double strands—that is, each thread is carried back on itself within a single shed of the warp. 55 The two weft threads are successively laid and looped with each other at opposite edges in symmetrical arrangement at each side, so that reinforced selvages of uniform structure, strength, and resistance to pulling are 60 produced.

For this purpose, there are provided a pair of transversely-reciprocating horizontally-disposed needles 48 and 49, and a pair of vertically-reciprocating rotary looper shafts 65 50 and 51 carrying looper elements, herein-

after more fully referred to. The needles are disposed in horizontally-aligned relation with each other and are secured in diagonally projecting arm-supports 52 and 53 respectively mounted on reciprocating slide rods 54 and 55 slidably supported in suitable bearings or guides 56 and 57 secured to the uprights 12 and 13. At one end, the rods are provided with eared sleeves 58 and 59 pivotally connected by links 60 and 61 to the upper ends of rocker-arms 62 and 63 hinged at their lower ends to floor brackets 64 and 65 and respectively carrying rolls 66 and 67 which engage the grooves of cams 68 and 69 carried upon the shaft 16.

80 The weft threads are carried from spools 70 and 71, mounted upon suitable supports 72 and 73 through guide loops 74 provided on the respective arm-supports 52 and 53, to the needle eyes provided at the forward ends of the needles.

85 The vertically-reciprocating looper shafts 50 and 51 are mounted for vertical sliding and rotary movements in the vertical passages of a pair of bracket supports 75 and 76 secured upon the plate member 15; and at their upper ends are provided with annularly channelled collars 77 and 78 in which rings 79 and 80 are engaged and have trunnion connection with the yoke ends 81 and 82 of levers 83 and 84 pivotally supported upon brackets 85 secured to the inner side of the plate member 15. Rolls 86 and 87 are provided at the inner ends of the levers, which engage the grooves of cams 88 and 89 provided upon the shaft 31, and which are designed to impart alternate up-and-down movement to the loopers. Within pockets 90 and 91, provided in the respective brackets 75 and 76, there are provided gears 92 and 93 keyed upon the looper shafts to permit longitudinal movement of the latter, and engaged by horizontally-disposed rack members 94 and 95 provided at their respective inner ends with yoke portions 96 and 97 embracing the shaft 31, and carrying rolls 98 and 99 engaging the grooves of cams 100 and 101 provided upon the shaft 31, and adapted to reciprocate the racks and, through the gears 92 and 93, to rotate the 100 looper shafts to and fro through a quarter turn.

105 At the lower ends of the looper shafts there are provided forked flattened thread-engaging looper portions 102 and 103, one leg of each of these portions being longer than the other, and respectively provided upon one side with hooks 104 and 105 for engaging and drawing the thread downwardly into loop form.

110 The operation of the machine (Figs. 5 to 10) is as follows:

115 The weft thread *b* carried by the needle 48 is laid in a shed of the warp from the left and is carried beyond the right-hand edge 120

where the looper 103, moving downwardly, is engaged in flatwise relation between the needle and the strand of weft at one side, the hook 105 engaging this strand and carrying it downwardly. The needle 48 then starts its return movement, leaving the thread looped about the looper; and as said needle becomes free of the looper, the latter is rotated a quarter turn, as shown in Figs. 7 and 8, forming the loop held thereon so that its opening is in alignment with the needle 49. The needle 49 thereupon moves to the left into the successive shed of the warp passing through the space between the legs of the looper 103 and through the loop carried thereon, whereupon the looper shaft 51 is moved upwardly, shedding its loop which is now interwoven with the other weft thread. As the needle 49 reaches its fully projected position (Fig. 9) the looper 102 moves downwardly between the needle and thread, the thread being drawn downwardly by the hook 104 to form a loop; and thereupon, the needle is retracted and the looper 25 rotated a quarter turn (as shown in Fig. 10) to present the opening of the loop to the needle 48 which is then projected through it. With each operation of the needles the drum 33 is rotated to feed the warp and 30 wind up the woven fabric; and the harness 39 and reed 44 are operated in the usual manner to alternately raise and depress the warp and compact the weft.

A woven fabric is thus produced in which the weft is formed of two threads fed from opposite sides, and each supplied from a single source of supply, so that the machine may be continuously operated with less attention than is necessary with the usual type of loom, and without the complication and floor space incident to the shuttles or bobbins heretofore employed to feed the weft. Knitted selvages are produced at each edge by interweaving and looping the weft threads; and a tape or braid of symmetrical structure is provided which will withstand pulling strains and wear equally at each side.

I have illustrated and described a preferred and satisfactory embodiment of the invention, but it will be obvious that changes may be made therein, within the spirit and scope thereof, as defined in the appended claims.

Having thus described my invention, what I claim and desire to secure by Letters Patent is:

1. In a fabric weaving machine, warp feeding means, weft feeding means including a weft carrying element adapted to be projected between sheds of the warp, and looper means adapted to produce loops in a thread through which the weft thread carried by said element is passed.

2. In a fabric weaving machine, warp

feeding means, weft feeding means including weft carrying elements at each side of the warp adapted to be projected between sheds of the warp from opposite sides, and looper means adapted to produce loops in a thread through which the respective weft threads are passed.

3. In a fabric weaving machine, warp feeding means, weft feeding means including weft carrying elements at each side of the warp adapted to be projected between sheds of the warp from opposite sides, and looper means adapted to produce a loop in the projected portion of each weft thread through which the other weft thread is passed.

4. In a fabric weaving machine, warp feeding means, weft feeding means including weft carrying elements at each side of the warp adapted to be projected between sheds of the warp from opposite sides, and looper means adapted to engage and form a loop in the projected portion of each weft thread, the weft carrying means of the other weft thread adapted to be projected through said loop.

5. In a fabric weaving machine, warp feeding means, weft feeding means including weft carrying elements at each side of the warp adapted to be respectively projected between successive sheds of the warp from opposite sides, and looper means adapted to engage and form a loop in the projected portion of each weft thread, the weft carrying means of the other weft thread adapted to be projected through said loop.

6. In a fabric weaving machine, warp feeding means, weft feeding means including a weft carrying element adapted to be projected between sheds of the warp and retracted to lay double strands of weft thread having a bight at one edge, and looper means including a reciprocating loop element having a forked end adapted to be engaged and disengaged with said weft to produce loops in a thread through which said weft is passed, adapted to engage within said bight whereby another thread is woven in looped relation therewith.

7. In a fabric weaving machine, warp feeding means, weft feeding means including weft carrying elements adapted to be projected between sheds of the warp from opposite sides to alternately lay double strands of weft threads from opposite sides having bights at the respective projected ends, and looper means adapted to engage within said bights to form a loop in the projected ends of each weft thread through which the double strands of the other weft thread are passed.

8. In a fabric weaving machine, warp feeding means, weft feeding means including a pair of weft carrying needles disposed in horizontal relation, one at each side of the warp, and each adapted to carry a weft

- thread, means for alternately reciprocating said needles through the sheds of the warp, whereby the weft threads are alternately laid from opposite sides, and looper means adapted to engage the weft threads upon projection between the warp sheds to form a loop in the projected portion of each weft thread through which the other weft thread is adapted to be passed.
9. In a fabric weaving machine, warp feeding means, weft feeding means including a reciprocating needle, thread supply means from which a weft thread is adapted to be continuously supplied to said needle, means for reciprocating said needle through the shed of the warp, and looper means adapted to produce loops in a thread through which the weft thread carried by said needle is passed.
10. In a fabric weaving machine, warp feeding means, weft feeding means including a pair of reciprocating needles, one at each side of the warp, thread supply means for each of said needles from which a weft thread is adapted to be continuously supplied to said respective needles, means for alternately reciprocating said needles through the sheds of the warp, whereby the weft threads are alternately laid from opposite sides, and looper means adapted to engage the weft threads upon projection between the warp sheds to form a loop in the projected portion of each weft thread through which the other weft thread is adapted to be passed.
11. In a fabric weaving machine, warp feeding means, weft feeding means including a weft carrying element adapted to be projected between sheds of the warp, and looper means including a vertically reciprocating looper element adapted to be engaged and disengaged with said weft to produce loops in a thread through which said weft is passed.
12. In a fabric weaving machine, warp feeding means, weft feeding means including a weft carrying element adapted to be projected between sheds of the warp, and looper means including a vertically reciprocating looper element adapted to be engaged and disengaged with said weft to produce loops in the projected portions thereof.
13. In a fabric weaving machine, warp feeding means, weft feeding means including weft carrying elements at each side of the warp adapted to be projected between sheds of the warp from opposite sides, and looper means including a pair of vertically reciprocating looper elements adapted to be alternately reciprocated into and out of engagement with the weft to produce a loop in the projected portion of each weft thread through which the other weft thread is passed.
14. In a fabric weaving machine, warp feeding means, weft feeding means including weft carrying elements at each side of the warp adapted to be projected between sheds of the warp from opposite sides, and looper means including a pair of vertically reciprocating and rotatable looper elements adapted to be alternately reciprocated into and out of engagement with the weft to produce a loop in the projected portion of each weft thread and rotated to present said loop for the passage therethrough of the other weft thread.
15. In a fabric weaving machine, warp feeding means, weft feeding means including weft carrying elements at each side of the warp adapted to be projected between sheds of the warp from opposite sides, and looper means including a pair of vertically reciprocating and rotatable looper elements having a weft receiving opening therethrough, adapted to be alternately reciprocated into and out of engagement with the weft to produce a loop in the projected portion of each weft thread and rotated to present said opening and the loop for the passage therethrough of the other weft thread.
16. In a fabric weaving machine, warp feeding means, weft feeding means including weft carrying elements at each side of the warp adapted to be projected between sheds of the warp from opposite sides, and looper means including a pair of vertically reciprocating looper elements, each having a weft engaging hook, adapted to be alternately reciprocated into and out of engagement with the weft to produce a loop in the projected portion of each weft thread through which the other weft thread is passed.
- Signed at Bridgeport in the county of Fairfield and State of Connecticut this 17th day of May, A. D. 1926.
- JOHN E. FEFEL.
